UNITED STATES PATENT OFFICE.

ROBERT WIGHTON MONCRIEFF, OF NEWPORT PAGNELL, ENGLAND.

APPARATUS FOR SPINNING AND DOUBLING.

SPECIFICATION forming part of Letters Patent No. 714,933, dated December 2, 1902.

Application filed February 11, 1902. Serial No. 93,622. (No model.)

To all whom it may concern:

Be it known that I, ROBERT WIGHTON MONCRIEFF, a subject of His Majesty the King of Great Britain, residing at Newport Pagnell, 5 in the county of Buckingham, England, have invented a new and useful Improvement in Apparatus for Spinning and Doubling, (for which I have applied for a patent in Great Britain, No. 13,860, said application bearing 10 date the 8th of July, 1901; in Germany, dated April 5, 1902; in Austria, dated July 28, 1902; in Hungary, dated August 9, 1902; in Switzerland, dated July 26, 1902; in France, dated July 30, 1902; in Belgium, dated July 30, 1902, 15 and in Denmark, dated July 26, 1902,) of which the following is a specification.

This invention relates to apparatus for spinning and doubling, and has for its object to cause the yarn to be wound upon the spindle-blade (or upon the tube or bobbin) in a 20 very speedy and even manner and without the risk of "ballooning" and greasing of the rings or soiling of the yarn, while, furthermore, the yarn is subjected to less strain than 25 with ring-frames and the utilization of finer yarn for spinning rendered possible.

In order that this my said invention may be the more readily understood and carried into practical effect, reference is hereby made 30 to the accompanying sheet of illustrative drawings, wherein—

Figure 1 is a front elevational view, partly in section, of a rotating spindle provided with the twisting-disk in accordance with my invention, Fig. 2 being a side view thereof, also 35 partly in section, and showing a modification of the twisting-disk.

In the drawings, *a* represents the blade of the spinning or doubling spindle, which spindle 40 is rotatably mounted in a socket *b* in the spindle-rail *b* in any suitable manner, such spindle being driven positively by a band or the like passing around the wharve *c* in the usual well-known manner.

On the blade *a* of the spindle or on an externally-parallel removable tube or single-headed bobbin *a'*, placed on and fixed to 45 revolve with the said spindle, I mount a wooden or metal twisting-disk *d*, such disk being 50 bushed with wood, cork, felt, or other suitable material to minimize friction and pre-

vent soiling. The said twisting-disk *d* is fitted to revolve freely on the blade, tube, or bobbin aforesaid.

From the twisting-disk *d* one or more arms 55 *d'* project upward to a height corresponding to the greatest length of coppering taper required, such arms being given an outward inclination toward their upper ends. In lieu of the said arms *d'* I may employ an upwardly-projecting rim *e*, such rim being outwardly inclined or beveled upon its inner periphery from the lower toward the upper end.

The arms *d'* may be bent into eyes *d''* at their upper extremities for the yarn passing 65 through, or detachable hooks *d'''*, or the yarn may be fixed to such arms or to the upper edge of the said rim *e*.

The twisting-disk *d* is preferably given a truncated-cone shape, the largest diameter of 70 such cone being lowermost and arranged to rest upon the upper surface of the coppering-rail *f*, through an opening in which the spindle-blade (and tube or bobbin, if the latter be employed) passes, or the said lower end of 75 the twisting-disk may rest upon a leather, felt, or other washer *g*, interposed between such twisting-disk and the surface of the coppering-rail, such washer being either loose or attached to either the said disk or coppering- 80 rail.

Temper-bands *h* are provided for obtaining the necessary tension of the yarn being wound and for preventing the twisting-disk 85 *d* rising off the coppering-rail, such temper-bands or drag-cords being arranged to press against the conical surface of the said twisting-disk by means of weights or suitable springs. (Not shown.)

The tube or bobbin *a'* is preferably provided with an outwardly-projecting top flange *a''*, such tube or bobbin being formed of metal, wood, or other suitable material, or of wood or the like incased with metal.

The operation of my invention is as follows: The yarn is brought down from the rollers in the usual manner and passed through the eyes or their equivalents upon the arms or disk of the twisting-disk around the spindle-blade or the tube or bobbin, according to the nature of the work being performed. At starting the coppering-rail is set 95 100

at its highest point, and the cop is gradually built downward by the twisting-disk following such coppering-rail, the said disk always being beneath the part of the cop or spool 5 which is being built, so that the latter can be readily removed upward. The twisting-disk is drawn around by the pull of the yarn that is being spun or doubled, assisted by its own frictional contact with the blade of the 10 spindle or with the exterior of the tube or bobbin, according to the nature of the work being performed, as aforesaid, the said disk being caused to "lag" or travel at a slower speed than said spindle. In this manner the 15 yarn is wound on the spindle-blade, tube, or bobbin in a rapid and even manner.

The coppering-rail works in the ordinary manner, rising and falling, say, one and one-half inches, or the length of the tapered portion 20 of the cop, while at the same time it is lowered a very small distance after each traverse, thus gradually forming any length of cop the spindle is equal to. The coppering-rail is continually working up and down for 25 a short travel and has also a very slow motion bodily upward at the end of each short travel.

What I claim, and desire to secure by Letters Patent of the United States, is—

In apparatus for spinning and doubling, 30 the combination with a positively - driven spindle; of a spindle-rail; bearings in said spindle-rail in which said spindle is mounted; a suitably-actuated coppering-rail; a twisting-disk having a truncated-cone shape of which 35 the lowest part is greatest in diameter, such disk being loosely mounted on said spindle-blade and having its lower side in frictional contact with the said coppering-rail and being provided with an upwardly-projecting rim 40 having at its upper end hooks for the yarn passing through onto the spindle-blade, said rim being outwardly inclined toward its upper end; and the drag-cords arranged to press against the conical surface of the said twisting-disk to obtain the necessary tension of the 45 yarn and to prevent said twisting-disk rising off the coppering-rail, substantially as specified.

In witness whereof I have hereunto set my hand in the presence of two witnesses.

ROBERT WIGHTON MONCRIEFF.
